HAIR CLIPPER

John A. Hanley, Stamford, Conn., assignor to
Gillette Safety Razor Company, Boston, Mass.,
a corporation of Delaware

Application March 7, 1935, Serial No. 9,714

27 Claims.

(Cl. 30—43)

My present invention is concerned in its most specific application with hair clipping apparatus of the type used as a substitute for a razor, although in certain of its aspects the invention is applicable to other types of hair shearing or clipping apparatus, and to tools used for other purposes.

The invention is more especially concerned with various alternative embodiments of construction and in some respects with improvements upon the hair clipping heads disclosed and generically claimed in my copending application Serial No. 5,319, filed February 7, 1935.

An object of the present invention is to provide a construction of the above general type in which the coating shear plates are inherently correlated to admit of facility of direct assembly on the handle or holder without the use of any distinct latch plate apart from the handle.

Another object is to provide a device of the above type, which though provided with the V-shaped teeth, desirable for guiding the stubble to the shearing edge, is yet effective to shear close to the skin throughout the effective height of said V teeth.

Another object is to provide an apparatus of the above type admitting of ready replacement of tools of various types and for various uses, the tool handle affording a universal holder for any of a number of tool carriers, each having a distinctive tool.

A feature of the invention is the correlation of the fixed and movable shear plates into a unit in which one of said elements straddles or encloses the other and in which the unit has a central fin, keel, rib or stem longitudinally of the cutter, to extend into a corresponding groove in the mounting handle or head from which the straddled or movable shear plate is operated.

In one type of combination the fin or stem is on the fixed shear plate, the motor being connected to the movable shear plate through an elongated slot in said fin. In another type of construction, the fin or stem is a part of the inner or movable shear plate, the shear edges of which are straddled by the fixed shear plate. The moving shear head may in one embodiment be generally T-shaped in cross-section, the fixed shear plate straddling the head of the T, which is preferably beveled at its edges. In another embodiment, the movable shear plate may be generally Y-shaped, the arms of the Y affording inherently beveled edges over which

the shear edges of the fixed shear plate are in-turned.

The shearing head in each of the latter embodiments may be secured to the handle or casing of the tool by spring latch plates fixed to the casing and snapped over the ends of the fixed shear plate. Where the fin or stem is fixed to the handle casing the latching is preferably by a spring pressed latch pin protruding into the casing and engaging the fixed fin or stem.

While the various embodiments lend themselves particularly to symmetrical shear heads with two sets of parallel shear edges, it is within the scope of the invention to form the shear teeth directly on the exposed edge of a plate directly positioned at one edge in the groove of the casing in place of the fin or stem of the other embodiments. The fixed shear plate, in that case would straddle said shear edge and would be fixed near its opposite edge to the casing or handle.

Another feature of the invention is the progressive thinning of the stock of the fixed shear plate across its beveled shear edge to be substantially proportional at each part of the width of said edge to the width of the corresponding portion of the V-shaped slots, by which arrangement the skin will be brought into close contact with the moving shearing plate throughout the effective width of each shearing edge.

30 In the accompanying drawings, in which are shown one or more of various possible embodiments of the several features of the invention,

Fig. 13 is a fragmentary view similar to Fig. 11 showing another embodiment.

Fig. 14 is a fragmentary side view of another embodiment.

Fig. 15 is a fragmentary front view of the embodiment of Fig. 14.

Fig. 16 is a disassembled perspective view of a desirable form of shear head mount, and

Fig. 17 is a fragmentary view in longitudinal cross-section illustrating the assembly of the shear head mount of Fig. 16.

Referring now to the embodiment of Figs. 1 to 4, there is shown the fragment of a handle casing 20 in which is mounted a motor (not shown) and preferably of substantially the construction described and claimed in my copending application Serial No. 757,755, filed December 17, 1934.

The front of the casing has a groove 21 extending longitudinally across the width of the handle, which lodges the shear head, now to be described. The two coacting elements of the shear head comprise an outer or fixed shear plate or element 22 and a complementary inner or reciprocating shear plate or member 23. The outer element in the present embodiment is a composite unit comprising a sheet of stainless steel presenting a flat shear face 24, having inturned sides 25 with parallel spaced shanks 26 which straddle a solid metal block 27 to which they are welded. The block with the shanks welded thereto forms a central fin, keel, stem or rib to lodge in the groove 21. As shown, the shear face 24 is spaced by the inturned sides 25 from the block 27 to form an open channel of equi-lateral trapezoidal cross-section, of which the wider base constitutes the shearing face 24, the narrower base being determined by the upper end of the block 27.

The movable plate 23 is lodged in said channel, and in a preferred embodiment shown, comprises a channel-shaped plate of stainless steel engaging the block 27 at its central web 28, the outwardly flaring sides 29 engaging the inturned sides 25 of the fixed plate. The outer edges 30 of the movable plate extend obliquely of the stock in a common plane parallel to web 28, as shown, and closely engage the shear face throughout their lengths and widths, as shown in Fig. 1.

The shearing conformation is generally similar to that shown in the copending application Serial No. 5,319, above referred to, and will be but briefly described here.

The edges 30 of the movable plate 23 are toothed, as shown in Figs. 5 and 6, by undercutting from the outer or flaring sides 29 of plate 23 to form V-shaped grooves 31 which become progressively wider and deeper from the apex 32, such grooves cutting through the obliquely extending shear edges 30 of said plate to form the triangular serrations 33 thereat.

The shearing conformations of the fixed or enclosing plate 22 are formed by slots 34 transversely of the lateral edges of the shear face thereof. These slots 34, as shown in Fig. 7, may be formed by beveled milling cutters and are spindle-shaped with maximum length and width at the outer face and minimum length and width at the inner face of the plate, the walls of said slots extending obliquely through the thickness

of the stock. The fold line between the shear face and the inturned side 25, as shown, is not along the median lines of the spindle-shaped slots 34, but somewhat in back of said median line and particularly along the line 35 in Fig. 7, so that, as best shown in Fig. 1, the upper ends of the slots 34' are nearer the fold edge than the lower ends 34 of said slots, which latter thus greatly facilitate shedding of clippings.

As a safeguard against possible abrasion of the face by the end edges of the shear face 24, it is desirable to provide narrow integral extensions along said ends which are turned inwardly, as at 36, into snug engagement with the shear face to afford a rounded smooth edge.

The shear head is affixed to the casing, preferably by means of a pair of latch pins 37 extending through corresponding bores 38 in the casing and at their inner ends engaging corresponding depressions 39 in the fin or stem 26-27 of the shear head. These pins preferably protrude at right angles from a U-shaped leaf spring 40, to which their outer ends are attached at 41, said leaf spring being secured to the casing at the lower ends of its U arms by means of screws 40'. It will be apparent that the shear head when pressed into the groove 21 will ride over the inner ends of pins 37, which will then snap into the depressions 39 and thereby affix the shear head into operative position. The spring 40 has an outstanding lip 40' for facility in manipulation when the shear head is to be removed from the handle casing. The head is preferably lodged snugly at inturned sides 25 against the formation of the casing, and the innermost end of the fin or keel 26-27 is spaced as shown from the bottom of groove 21.

The reciprocating lever 42 operated from the electric motor (not shown) protrudes through an elongated central slot 43 in the mounting fin 26-27 and its upper extremity 44 engages a corresponding rectangular narrow central slot 45 of the inner shear plate 23 for operating the latter.

In use, the device is pressed at the shear face 24 into face to face engagement with the surface to be clipped and the clipping, of course, occurs at the contact face between the edges of the inner moving shear plate 23 and the shear stop portions 34 in the outer or shear face 24, the clippings being readily shed through the undercut portions 31 of the serrations and along the flaring sides 25 of the shear plate 22 and through the elongated portion 34' of the shear slots 34.

A desirable refinement in the construction is the grinding of the bearing face to be progressively thinned from its lateral edges to the region of the apices of the serrations as at 46. Thus the thickness of the bearing metal stock is a maximum at the lateral edges of the shear face where the shear slots 34 are widest and is a minimum at the inner ends of said shear slots where they are narrowest. The stock is progressively thinner between said parts of maximum and of minimum thickness, so that the thickness of the stock along the shearing width at each portion is approximately proportional to the width of the corresponding part of the V-shaped shear slot.

By this arrangement, as best shown in Figs. 8 and 9, substantial assurance is had that the clipping will be close to the skin throughout the effective length of the shear slots and serrations. Thus, in those regions where the width of the teeth is a minimum and the space between them is a maximum, the skin may, under pres-

sure of the shear face thereagainst, protrude inward as at 47 in Fig. 8, through the thickness of the shear plate 24 for close engagement with the inner plate edge 30. Nearer the roots of the slots 34, however, where the width of the teeth is a maximum and the space therebetween a minimum, the skin cannot be depressed to the extent shown at 47 and the stock is correspondingly thinned, as best shown in Fig. 9, to permit the skin at that region, as at 47, also to come into engagement with the inner shear plate edge 30. In actual practice it is found that for best operation the distance between the centers of successive shear teeth (and of successive shear serrations) should be as little as .0025 inch.

The embodiment of Fig. 10 represents but a slight modification with respect to that of Fig. 4, in that, in place of the channel bar-shaped movable plate 23, a solid movable plate 50 trapezoidal in cross-section is employed. The wider face of said trapezoidal plate is undercut at 51 between the lateral track edges 52 at which the serrations 53 are formed, and the notch 54 in the narrow base of said plate performs the functions of slot 45 in Fig. 4.

In the alternative embodiments of Figs. 11 to 15, the parts of the shear head are, generally speaking, reversed in that the element with the keel or stem is the reciprocated portion, the exposed operating portions of which are straddled by the fixed shear element.

In the embodiment of Fig. 11, the movable plate is, generally speaking, a T bar, the keel or stem 56 of which extends into the casing notch 57 and is either formed integral or has spot welded thereto the T-head 58, which extends symmetrically from opposite faces of stem 56. The lateral edges of the T head are beveled as at 59 and formed with the serrations 60 substantially identical with those in Figs. 5 and 6. The fixed shear plate is in the character of a sheath 61 with inturned edges or borders, extending under and straddling the T head and engaging the end of the casing 62 at their inner extremities. The obliquely extending or beveled sides 63 of said sheathing plate 61 are slotted exactly as above described in connection with Fig. 7.

Inasmuch as the keel or stem 56 in this embodiment reciprocates, the latching construction of Figs. 1 and 2 cannot be applied. In the present embodiment accordingly, a spring latch plate 65 is fixed as by screw 66, one at each side of the casing. Each latch plate has a narrow in-turned flange 67 overlapping the corresponding end of the outer or fixed sheathing shear plate 61, as shown in Figs. 11, 12 and 17. The in-turned flanges are preferably centrally indented or rounded, as at 68, to equalize the pressure along the oblique lateral shearing edges 69.

The stem of the T head or rib is provided with a central notch 70 into which protrudes the extremity of the operating lever 71 and the inner end of said T stem is preferably spaced from the bottom of notch 57 to reduce friction. In this embodiment, the apparatus is used like a hoe type of safety razor, as distinguished from the embodiment of Figs. 1 to 10, in which the device is held at right angles to the face.

The embodiment of Fig. 13 is generally similar to that of Fig. 11, except that instead of a T beam for the movable shear plate, a Y-beam is employed. This Y-beam may be made up of a pair of similar plates 75, each bent along an obtuse angle and spot welded together at the stem-

5 forming part 76 to afford the diverging arms 77 of the Y. As in the embodiment of Fig. 1, the upper edges of the stock are cut obliquely so that the upper ends of the Y-arms extend in a common plane at right angles to the stem 76.

The fixed shear plate 78 straddles the gap between the Y-arms and is laterally inturned, as at 79, to snugly engage the outer faces of said arms 77, as shown, and to be retained between the Y-unit and the correspondingly channelled end 80 of the casing 81.

In this case, of course, the outer face of the fixed plate serves as the shear face, for use of the device in the same manner as in the embodiment of Figs. 1 to 10. The same latch plates 85 are preferably used to assemble the parts, as in the embodiment of Figs. 11 and 12. The serration of the Y edges and the slotting of the fixed or sheathing plate is substantially the same as in the other embodiments.

Figs. 14 and 15 show an embodiment which differs from the others in affording but a single instead of twin pairs of shear edges. For this purpose the beveled serrated shear edge 82 is formed at the outer end of a rectangular plate 83, which fits with clearance into the groove 84 of the handle casing but bottoms in slot 24 thereof. The coacting fixed shear plate 85 in this embodiment serves as the means for holding the movable plate 83 assembled to the device. For this purpose the fixed shear plate is attached to one side of the casing by appropriate means and bridges over the beveled outer edge of the movable plate, the outer edge of said fixed plate being bent over at 86 to straddle said movable plate. The movable plate is serrated and the fixed plate slotted substantially exactly as in Figs. 5, 6 and 7. The fixed plate may be attached to the casing, preferably by a latching plate 87 held by pins 88 which may be fixedly mounted in the beveled forward end 89 of the casing. The pins 88 pass through corresponding openings (not shown) in the fixed shear plate and have notched heads 89 which pass through key slot 90 in the latch plate 87. The lateral shifting of said plate 87 brings the notched heads into the narrow portions of the slots 90 for firmly affixing the shear plate 85 and its latch plate 87.

Preferably an auxiliary holder plate 91 is attached by means of screws 92 to the other inclined face 93 of the casing. The outer edge of plate 91 has a beveled edge 91', the width of which engages the extremity of inturned edge 86 of the fixed plate 85 and prevents the latter from turning outwardly.

In each embodiment the stock of the outer or shear plate may be ground to be progressively thinned, as shown at 48 in Fig. 1, along the length of the shearing slots.

While the handle casing may be made of two complementary unitary pieces, a casing proper 85 and a cover 86, it is desirable, according to one feature of the invention, to afford a detachable tool mount 97 for the shaving head, said mount constituting the front or nose of the casing. In a desirable embodiment, this mount piece has a unitary key 98 along the inner face thereof to fit into a corresponding key-way 99 in the front of the casing body. The front of said nose piece 97 has the longitudinal groove 100 for mounting the shear head. The nose piece is affixed to the casing proper, preferably by a pair of screws 101 extending through slots 75 102 in the thickness thereof with their heads

countersunk, as at 103, in the bottom of the groove 102. The nose piece has a central port 104 through which the operating lever 105 protrudes for engagement with the movable piece of the shear head. Slots 102 are preferably wider along the length of mount piece 97 than is the diameter of screws 101, which permits of adjustment of the nose piece 97 properly to center the same with respect to lever 105.

It will be understood that by the provision of the separate nose piece 97, it is possible to use one common casing and motor head for any of a variety of tools including shear heads, massaging heads, or the like, each nose piece being specially conformed at its face for the particular tool it carries and having a common rear face conformation with key 98 to be affixed to and operated from the motor carrying handle piece 95-96 which thus serves for universal use with a great variety of tools.

It will thus be seen that there is herein described apparatus in which the several features of this invention are embodied, and which apparatus in its action attains the various objects of the invention and is well suited to meet the requirements of practical use.

As many changes could be made in the above construction, and many apparently widely different embodiments of this invention could be made without departing from the scope thereof, it is intended that all matter contained in the above description or shown in the accompanying drawings shall be interpreted as illustrative and not in a limiting sense.

I claim:

1. Hair clipping apparatus comprising a handle casing having a guide track longitudinally of its end, coacting shear plates mounted on said handle and including a plate element extending substantially the length and width and protruding above said track and protruding laterally beyond the front of said casing, said element having an edge with shear teeth, a complementary shear element, means for releasably securing one of said plates in fixed position with respect to said casing, means protruding from said casing for reciprocating the other of said plates, the fixed shear plate having an inturned edge straddling the shear edge of the movable plate and having shear teeth across said inturned edges conformed as slots with closed ends, and means to maintain said inturned edge from separation relative to the coacting shear element.

2. Hair clipping apparatus comprising a shearing unit including a fixed outer shear plate having inturned parallel margins, transversely slotted to afford shear teeth, a movable shear plate straddled and enclosed by said fixed plate and laterally serrated for shearing coaction therewith, the outer of said coacting plates having portions of said shearing conformations inturned and extending at an inclination inward toward each other under the movable shear plate, one of said plates having rigid therewith, a stem extending longitudinally midway of the width thereof and adapted to be lodged in a corresponding notch longitudinally of the end of a handle casing.

3. Hair clipping apparatus comprising a casing, a fixed shear plate extending laterally beyond the sides of the front of said casing and having symmetrically inturned side extensions, a fixed block interposed and secured between said extensions and defining an open channel between said block and said plate, the fold edges of said plate be-

ing transversely slotted to afford shear teeth along the margins of the otherwise continuous plate, and a shear member slidably positioned within said channel and serrated at its opposite edges for coaction with said slots, said shear member having a notch in the middle of its base, and said metal block having a longer notch to afford access for reciprocation of said shear member.

4. The combination set forth in claim 3 in which the plate affords a trapezoidal channel with the block at the narrower base thereof and in which the movable shear member comprises a channel bar with flaring sides engaging the sides of the channel and in which the width of the edges of said bar extends in direct engagement with the wider base of the trapezoidal channel.

5. The combination set forth in claim 3 in which the plate affords a trapezoidal channel with the block at the narrower base thereof and in which the movable shear member comprises a solid trapezoidal rod substantially filling said channel.

6. Hair clipping apparatus comprising a motor enclosing handle casing having a notch longitudinally of its operating end, a shear head including a stem lodged in said notch, a shear plate structure rigid with said stem, said structure having parallel opposite shear edges and determining an open channel above said stem, a coacting movable shear plate slidable in said channel, a motor operating lever protruding through said notch, through an elongated slot in said stem and into a corresponding notch in said movable plate and a latching pin extending through a passage in said casing into a corresponding depression laterally of said stem and a spring fixed to said casing urging said pin into latching position.

7. Hair clipping apparatus comprising a carrying head having a notch at one end across the width thereof, a movable shear member having a fin guided in said notch and having a plate beveled and serrated at its opposite edges, a coacting shear plate extending across the movable plate and having its edges infolded to sheathe the beveled shear edges thereof, said infolded edges transversely slotted to afford shear edges coacting with the serrations of said movable plate, and means removably attaching said sheathing plate in fixed position on said carrying head.

8. Hair clipping apparatus comprising a handle casing, a movable shear piece having a fin slidably lodged in a corresponding notch along the end of said handle casing for reciprocation therewith, a plate rigid with said fin affording lateral serrated shear edges, a coacting shear plate, and means engaging the ends of said coacting plate and removably securing the latter in fixed position on said head.

9. Hair clipping apparatus comprising a head, a moving shear piece having a fin slidable in a corresponding notch along said head to be reciprocated therewith, a transverse plate rigid with said fin affording lateral serrated shearing edges, a coacting shear plate and end plates attached to said head and overlapping the ends of said coacting plate to hold the latter in fixed position.

10. Hair clipping apparatus comprising a head, a double edged beveled and serrated shear plate unit including a median fin lodged in a corresponding notch in said head, for reciprocation therewith, a coacting fixed shear plate extend-

ing across said beveled plate and having its edges folded under said beveled edges and transversely slotted for shearing coaction with said serrations, and holder plates secured to the opposite ends of said head and overlapping the ends of said fixed shear plate to retain the latter in position.

11. Hair clipping apparatus comprising a head, a moving shear plate of T-beam cross-section, having its stem lodged in a corresponding notch in the end of said head and having the ends of the T-head beveled and serrated, a fixed shear plate covering said T-bar head and having its edges folded under said beveled serrated edges, said folded edges being transversely slotted to afford shear teeth coacting with those of said movable plate and means coacting with said fixed plate to secure the latter to said head.

12. Hair clipping apparatus comprising a head, a Y-beam shaped shear plate unit having its stem lodged in a corresponding notch in said head, and its diverging protruding arms terminating in a common plane, and thus affording opposite beveled edges, said edges serrated, a fixed shear plate superposed over said Y and infolded about said beveled edges and transversely slotted for shearing coaction with said serrations, and means affixing said fixed shear plate to said head and retaining the parts in assembled relation.

13. Hair clipping apparatus comprising a head, a movable shear unit having a fin lodged in a corresponding notch in said head and adapted to be reciprocated therealong, said shear unit having opposite shearing edges symmetrical with respect to said fin, a fixed shear plate superposed over said movable unit and coacting with the opposite shear edges thereof, holder plates attached at opposite sides of said head and overlapping the opposite ends of said fixed shear plate, said holder plates being symmetrically rounded to engage the shear plate along a median line thereof for equalizing the pressure at the two shear edges.

14. Hair clipping apparatus comprising a head, a movable shear unit comprising a solid plate lodged at one edge in a corresponding notch in said head, and having an exposed beveled serrated shear edge and a coacting fixed shear plate secured to said head and having its edge folded and engaging the oblique face defined by the beveled edge of said movable plate, said folded edge being transversely slotted at the fold edge to afford shear teeth coacting with the serrations of said movable plate.

15. Hair clipping apparatus including a beveled head having oblique sides, a movable serrated beveled shear plate lodged at one edge in a corresponding notch at the front of said head, a coacting fixed shear plate fixed near one edge to one of the oblique sides of said head and folded at its other edge about the serrated beveled edge of the movable plate, said folded edge transversely slotted to afford shear teeth coacting with those of the movable plate, and a retainer plate attached to the other oblique face of the head, and having its free edge overlapping the free extremity of the infolded edge of said fixed plate.

16. Hair clipping apparatus including two contacting shear members, comprising an outer plate with a spaced series of narrow V-shaped shear slots having apices and diverging to a maximum width at the exposed edge of the plate and an inner shear plate with shearing serrations, the outer plate being of thickness, taper-

ing inward from the edge of the plate, the thickness at each part thereof being directly proportional to the width of the corresponding portion of the V-shaped shear slot.

17. Hair clipping apparatus comprising an inner movable shear plate having a set of lateral shearing serrations, an outer fixed shear plate of sheet metal straddling said serrated edge, said fixed plate having transverse shear slots at said straddling edge, said shear slots being generally V-shaped at their inner or shear surface, and diverging to maximum width at the exposed edge of the plate, the thickness of said outer plate along the shearing width thereof being a maximum along the wider portions of the V slots and a minimum near the apices of the V notches, said thickness tapering for substantially direct proportionality to the width of the corresponding portions of the V notches.

18. In apparatus of the character described, a casing, a removable tool carrying mount having a transverse key connection with respect to said handle, and operating means extending through a corresponding passage in said mount for operating a tool, screws extending through corresponding slots in said mount, threaded into the front of said handle, said slots elongated to permit of minor adjustment of said mount for proper setting of a tool relative to the operating means.

19. In apparatus of the character described, the combination of a handle having a tool operating lever protruding through the front thereof, a removable mount keyed to the front of the handle and having a longitudinal groove in its forward end to lodge a tool, screws having their heads below the bottom of said groove and affixed in the forward end of said mount, the shanks of said screws having clearance in said mount to permit minor adjustment thereof prior to tightening the same, for coordination of the tool with respect to the operating lever therefor.

20. In apparatus of the character described, a shearing head including an inner movable serrated plate, an outer fixed plate having its flat surface straddling the shear edge of the inner plate and slotted across said shear edge to afford shear teeth, said outer plate having lateral extensions beyond the slotted portions thereof, said extensions infolded to afford protective edges against injury to the face.

21. Hair clipping apparatus comprising a handle casing having a guide track longitudinally of its end, coacting shear plates mounted on said handle and including a plate element extending substantially the length and width and protruding above said track, said element having a bevelled edge with shear teeth, a complementary shear plate conformed to said bevelled edge and having an inturned margin extending along the under face of said bevelled edge and enclosing and straddling the exposed area of said first plate and having teeth coacting with those of said first plate, means for releasably securing one of said plates in fixed position with respect to said casing and means protruding from said casing for reciprocating the other of said plates.

22. Hair clipping apparatus comprising a head, a movable shear plate unit of T-beam cross-section, having its stem lodged and guided in a notch in said head and having shear edges on opposite edge portions of the T-head, a fixed shear plate having shear edges in coaction with those of said movable unit and means secured to said head overlapping the opposite ends of

said fixed shear plate to hold the parts assembled.

23. Hair clipping apparatus comprising a head, a moving shear plate of T-beam cross-section, having its stem guided for movement in the end of said head and having the ends of the T-head beveled and serrated, a fixed shear plate covering said T-bar head and having its edges turned under said beveled serrated edges, said turned edges being transversely slotted to afford shear teeth coacting with those of said movable plate and means coacting with said fixed plate to secure the latter to said head.

24. Hair clipping apparatus comprising a handle having a longitudinal notch along its forward end, a movable plate lodged and guided in said notch but substantially free from frictional engagement therewith and having a bevelled shear edge, operating means within said handle for reciprocating said plate, and a coacting fixed shear plate secured to said handle, having an in-turned margin conformed to said bevelled edge, enclosing and straddling the shear edge of said movable plate and extending along the under face thereof and thereby retaining the same in assembled position, said straddling edge being transversely slotted to afford shear teeth coacting with those of said movable plate.

25. Hair clipping apparatus comprising a shearing unit, including a central stem adapted to be reciprocated in a corresponding slot in the end of a handle casing, said unit including outwardly extending flat shearing flanges rigid with and in a plane substantially at right angles to

said stem, a complementary shear plate, the inner of said two plates having serrated lateral edges, the outer of said plates having margins extending over and covering the lateral edges of the inner plate and said margins being transversely slotted to afford shear teeth, one of said shear plates being movable relative to the casing, said plate having a conformation at its lower part from which it is reciprocated.

26. Hair clipping apparatus comprising a head having a longitudinal notch, a movable shear member having a stem lodged in said notch and having two bevelled shear edges between parallel planes at right angles to said stem, and separated by a distance greater than the thickness of said stem, a coacting shear plate laterally sheathing the shear edges of the movable shear member and having inturned margins extending thereunder, said sheathing plate being transversely slotted across the straddling and sheathing edges to form shear teeth, and means securing said sheathing plate in fixed position relative to said head.

27. In apparatus of the character described, a handle having a key element along its end, a replaceable tool carrying mount having a complementary key element, fastening means for rigidly attaching said mount to said handle with said key elements in coaction and operating means extending through passages therefor in the two elements of said key connection for operating a tool.

JOHN A. HANLEY.
